US00D966866S

(12) **United States Design Patent** (10) **Patent No.:** **US D966,866 S**
Woodley et al. (45) **Date of Patent:** **** Oct. 18, 2022**

(54) **LOCK AND UNLOCK INDICATOR**

(71) Applicant: **dormakaba USA Inc.**, Indianapolis, IN (US)

(72) Inventors: **Jamison D. Woodley**, Indianapolis, IN (US); **Yang Wei**, Shenzhen (CN)

(73) Assignee: **dormakaba USA Inc.**, Indianapolis, IN (US)

(**) Term: **15 Years**

(21) Appl. No.: **29/696,700**

(22) Filed: **Jun. 29, 2019**

(51) **LOC (13) Cl. 08-07**

(52) **U.S. Cl.**

USPC **D8/343; D8/331**

(58) **Field of Classification Search**

(57) **CLAIM**

The ornamental design for a lock/unlock indicator, as shown and described.

DESCRIPTION

FIG. 1 is a front perspective view of a lock/unlock indicator illustrating my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating portions of the lock and unlock indicator that form no part of the claim.

1 Claim, 4 Drawing Sheets
